(57) **CLAIM**

The ornamental design for a rim guard with spout for paint can as shown and described.

DESCRIPTION

FIG. 1 is a left side view in elevation of my design; FIG. 2 is a right side view in elevation thereof; FIG. 3 is a front view in elevation thereof; FIG. 4 is a rear view in elevation thereof; FIG. 5 is a perspective view from above of the design in FIG. 1; FIG. 6 is top view thereof; FIG. 7 is a bottom view thereof; and, FIG. 8 is a cross-section view taken from FIG. 6. The broken lines consisting of equal length dash lines in FIG. 8 depict parts of the paint can that form no part of the claimed design.
